UNITED STATES PATENT OFFICE

2,197,037

TIE ROD BOOT

Allen F. Gardner, Detroit, Mich., assignor to Chicago Rawhide Manufacturing Company, Chicago, Ill., a corporation of Illinois

Application May 17, 1937, Serial No. 143,094

5 Claims. (Cl. 287—90)

The purpose of this invention is to provide a flexible closure boot for the ball-and-socket joint at the end of the tie rod in the steering gear of an automobile, which boot will retain the grease used in lubricating the joint, will prevent the entrance of dirt, mud and water from the road, and will conform without resistance to the turning and tilting movements which are constantly occurring between the parts of the joint, all without interfering in any way with such movements, and without becoming ineffective as a result thereof.

The new boot is light and compact, is inexpensive to manufacture and easy to apply, and when placed in position will remain there without becoming dislodged.

This boot has filled a long felt want in the automotive industry, where engineers have striven for years without success to work out a practical form of closure for a tie rod end joint. While the boot is particularly applicable to a tie rod end joint it can of course be used to enclose other kinds of joints.

Other more specific objects and advantages of the invention will be evident to those skilled in the art upon a full understanding of the boot and the way in which it is used.

A preferred embodiment of the invention, and several slightly different modifications thereof, are presented herein for the purpose of exemplification, but it will of course be appreciated that the invention is susceptible of being incorporated in other structurally modified forms coming equally within the scope of the appended claims.

In the accompanying drawing:

Fig. 1 is a side view of the ball-and-socket joint at one end of a tie rod, equipped with the new boot;

Fig. 2 is a vertical section through the center of the joint and boot;

Fig. 3 is a diametric section through the boot, before being applied to the joint;

Fig. 4 is a partially sectioned side view, showing a modification of the boot;

Fig. 5 is a similar view, showing another modification of the boot; and

Figs. 6 and 7 are similar views, showing still other modifications.

The construction illustrated in Figs. 1, 2 and 3 will first be described. The ball-and-socket joint shown in these views includes a hollow head 10 which is provided with a socket 11, and a tapered stud 12 which is provided with a ball 13. The ball 13 is retained in the socket 11 by means of a plug 14. The stud 12 projects upwardly from the head 10 and is free both to rotate and to tilt

with respect to the head. A tie rod 15 is inferiorly threaded at one end and is screwed over a threaded stem 16 on the head, and a steering arm 17 is apertured at one end and is wedged down over the stud 12 by means of a nut 18 on the threaded upper end of the stud.

The closure boot for this ball-and-socket joint includes a formed leather jacket 19 which is preferably made in one piece. The jacket 19 is provided with a small opening at its upper end 20 and a large opening at its lower end 21, with a connecting wall portion which is bulged out in all directions between the ends, which bulged out portion permits of endwise extension and contraction of the jacket, as well as sidewise bending of the same, after the fashion of an accordion.

The upper and lower ends 20 and 21 of the jacket are secured to sheet metal rings 23 and 24. The upper ring 23 is adapted to be forced down over the tapered stud 12 into pressed-fit engagement with the same at a point a short distance above the upper surface of the head 10. The lower ring 24 is similarly adapted to be forced down over a machined portion 25 of the head 10 into pressed-fit engagement with such portion.

The ring 23 is made in two interfitting sections, 26 and 27, on the order of a grommet. The section 26 is characterized by a top flange 28 and a downwardly extending tubular neck 29, while the section 27 is characterized by a bottom flange 30 and an upwardly extending tubular neck 31. These sections are sleeved together as far as the neck 31 will permit, with the edge of the neck 29 spun outwardly against the bottom flange 30 to secure the sections together. The constricted upper end 20 of the jacket 19 fits snugly but rotatably between the top and bottom flanges 28 and 30 of the ring.

The ring 24 is made in one piece and is characterized by a tubular neck 32 and a bottom flange 33. The outer edge of the bottom flange 33 is reversely bent, and the lower end 21 of the jacket 19 is clamped immovably between the flange 33 and the reversely bent outer edge thereof.

With this construction, the relatively movable parts of the ball-and-socket joint are completely protected, and no appreciable resistance is offered to any movement of the parts. The boot can be applied easily to the joint without requiring the use of any special tools.

In the modification shown in Fig. 4 the leather jacket 34 is made up from two centrally apertured flat disks 35 and 36, which disks are sewed together

about their peripheries. The upper mounting ring 37 is hollowed out adjacent its center to provide a space about the inner margin of the disk 35, and a small metal ring 38 is positioned in the 5 hollowed out portion in tightly gripped engagement with the inner margin of the disk 35. This ring 38 turns with the disk 35 and prevents the inner margin of the latter from being pulled out from between the opposed outer portions 39 of 10 the ring 37, which outer portions slidably engage the disk 35 in sealed association with the same.

The lower mounting ring 40 is clamped down against the top of the head 41 upon an interposed sealing gasket 42 of any suitable material and is 15 held tightly against the gasket by having its lower edge 43 spun into an annular groove 44 cut in the periphery of the head.

In the modification shown in Fig. 5 a formed one-piece leather jacket 45 is employed and the 20 upper inturned end 46 of the jacket is provided with an upstanding flange 47. The sheet metal ring 48 at the upper end of the jacket is shaped to conform to this flange 47, thereby providing an interlock of L-shaped radial section between 25 the jacket and the ring which decreases any possibility of the jacket working out of the ring at any point. In this modification the lower mounting ring is dispensed with and the lower end 49 of the jacket is instead drawn up tightly 30 into a groove 50 in the head 51 by means of a tensioned metal clamping band 52.

In the modification shown in Fig. 6 a jacket 53 of some moulded rubber-like material is employed. The upper end 54 of this jacket is formed 35 into a downwardly opening channel which tends to close upon itself under its own resiliency, and an upstanding metal flange 55 on a sheet metal mounting ring 56 is slidably positioned within this channel. The ring 56 is provided with an out- 40 turned flange 57 which overlies the upper end 54 of the jacket and prevents the latter from becoming disassociated from the flange 55 on the ring.

In the modification shown in Fig. 7 another 45 moulded jacket construction is shown. In this form the upper end 58 of the jacket is moulded to slidably embrace a radial flange 59 on a metal mounting ring 60.

I claim:

50 1. As an article of manufacture, a closure boot for application to relatively rotatable parts of a joint, as a complete permanently assembled and self-contained unit, consisting of a tubular jacket of flexible material, and metal rings permanently 55 mounted on the ends of the jacket in axially separated planes for sealed engagement with

relatively rotatable parts of the joint, one of said rings slidably embracing one end of the jacket for rotation with respect to the same.

2. As an article of manufacture, a closure boot for application to relatively rotatable parts of a 5 joint, as a complete permanently assembled and self-contained unit, consisting of a tubular jacket of flexible material, means for attaching one end of the jacket to one of the parts of the joint in sealed association with the same, and means for 10 attaching the other end of the jacket to another relatively rotatable and tiltable part of the joint in sealed association with the same, said last mentioned means being permanently connected to the jacket as an integral part of the boot and consisting of a two-part sheet metal grommet which is rotatably mounted on the jacket with its spaced sides in loosely embracing relation to the edge of the latter for pressed-fit engagement with the part of the joint to which attached.

3. As an article of manufacture, a closure boot for application to relatively rotatable parts of a 15 joint, as a complete permanently assembled and self-contained unit, consisting of a tubular jacket of flexible material which is made in one piece 20 with a small opening at its upper end and a large opening at its lower end and a connecting wall which is bulged out in all directions between such ends, which bulged out portion permits of end-wise extension and contraction of the jacket as 25 well as sidewise bending of the same, and metal rings secured to the upper and lower ends of the jacket for sealed engagement with relatively movable parts of the joint, one of said rings being 30 fixedly clamped to the jacket, and the other of said rings being loosely clamped to the jacket to permit relative rotation therebetween.

4. As an article of manufacture, a closure boot for application to relatively rotatable parts of a 35 joint, as a complete permanently assembled and self-contained unit, consisting of a tubular jacket of flexible material provided at one end with a circular inturned rim, and means for attaching the ends of the jacket to relatively movable parts 40 of a joint, the attaching means at one end consisting of a metal ring which is adapted to be press fitted to its particular part of the joint and contains an outwardly opening circular channel in which the circular inturned rim of the jacket is 45 snugly but rotatably retained.

5. In a universal joint, a cylindrical stud member, means disposed around said stud member defining an annular groove, and a flexible seal member having an end portion thereof slidably engaged in said groove.

ALLEN F. GARDNER.
